CLAIM

The ornamental design for a swimsuit, as shown and described.

DESCRIPTION

FIG. 1 is a front view of a swimsuit showing my new design;

FIG. 2 is a rear view thereof;

FIG. 3 is a left side view thereof; and,

FIG. 4 is a right side view thereof.

The broken line outline of a model assists in illustrating how the swimsuit may appear when in a position of use, but forms no part of the claimed design.
